TOBACCO DESUCKERING COMPOSITION
Albert Gathman, Belmar, N.J., assignor to Esso Research
and Engineering Company, a corporation of Delaware
No Drawing. Filed Aug. 27, 1962, Ser. No. 219,775
4 Claims. (Cl. 71—2.7)

The present invention is concerned with improved agricultural compositions as, for example, horticultural and crop spray oils, and with an improved tobacco desuckering composition. In particular, the invention is concerned with an improved agricultural composition for the desuckering of tobacco plants and eliminates plant injury which at times is caused by commercially available desuckering oil compositions.

The raising of fine high grade tobacco comprises a major industry in the United States. However, much of the labor which is required to grow this crop is utilized in manually breaking out the sucker buds to increase the leaf yield and the leaf quality. Thus, all available plant nutrients are utilized in producing large uniform leaves of high quality. In the raising of tobacco it is customary to break the main leader by hand when the tobacco plant begins to flower. This operation is called "topping." When the topping is accomplished, the plant nutrients induce rapid development of sucker growth at the junction of the stem and each leaf. In the past, as pointed out heretofore, to obtain the largest leaves possible, the suckers have been removed manually from two to four times in one season, which represents a very costly operation with respect to the expenditure of manpower.

In order to reduce this expenditure of manpower, various chemical compositions have been proposed and used for the purpose of desuckering tobacco plants without adversely affecting the tobacco quality. In accordance with the present invention, an improved chemical composition is utilized which is very effective in the control of the desuckering operation. The composition of the present invention comprises a critical quantity of a white oil, a petroleum sulfonate, an ether of triethylene glycol and an alkyl amine. Thus, the present invention produces a superior tobacco desuckering oil which has synergistic characteristics.

By the proper proportioning and the combining of selected ingredients, an emulsifiable oil is produced having desuckering properties. The oil of the present invention comprises a light colored product which is desired by the farmers. The components utilized in the present composition secure a synergistic effect which was not foreseeable. Furthermore, the oil of the present invention can be emulsified with water having a hardness up to 600 p.p.m. The base oil of the present invention is a white oil having a specific gravity in the range from about .86 to .89, preferably in the range of from about .88 to .89, and of a Saybolt color of at least 10. The viscosity is in the range of about 355 to 375 SSU at 100° F. for example, 365 SSU. The pour is less than 0 as, for example, in the range of about —15° F. to about —50° F. The oil passes the U.S.P. acid test (ASTM D-565-45) as, for example, about 2.5.

2

Other characteristics of a specific typical base oil of the present invention are as follows:

	Percent	Range Percent
Aromatics.....	0	0-5
Paraffins.....	8	6-12
One Ring Non-condensable Naphthalenes.....	26	20-30
Two Ring Non-condensable Naphthalenes.....	24	20-30
Three Ring Non-condensable Naphthalenes.....	19	15-25
Four Ring Non-condensable Naphthalenes.....	13	10-16
Five Ring Non-condensable Naphthalenes.....	6	4-10
Six Ring Non-condensable Naphthalenes.....	4	2-6

TYPICAL BOILING RANGE (CALCULATED FROM
10 MM. DISTILLATION)

	° F.	Range, ° F.
Initial.....	740	700-760
50%.....	883	860-900
90%.....	935	900-960
Final.....	975	960-990

The second ingredient utilized in the present invention comprises a petroleum sulfonate, preferably an alkali metal petroleum sulfonate such as a sodium petroleum sulfonate. This sulfonate is produced by conventional methods known in the art and has a molecular weight in the range of about 460 to 480. The percent sodium sulfonate ranges from about 61% to 65% and the specific gravity at 25° C. is in the range from about 1.02 to 1.05.

The third constituent comprises an ether of triethylene glycol, preferably a phenyl monoether of triethylene glycol. The fourth constituent comprises a particular tertiary amine made by condensing the two amino hydrogen atoms of a primary alkyl amine, in which the alkyl group is derived from soya oil, with ethylene oxide. The formula is

where n is 1 to 5 and preferably 3.

A composition was prepared in accordance with the present invention. The composition and the ranges are listed in the following table:

Table I

	Component	Vol. Percent	Vol. Per- cent Range
White Oil.....	97.90	90.0-98.0	
Petroleum Sulfonate.....	0.10	.01-.5	
Ether of Ethylene Glycol.....	0.75	.25-3.0	
Tertiary Amine.....	1.25	.5-3.0	
	100.00		

The above composition comprises a concentrate which is utilized to form an oil-in-water type of emulsion. The water content of the emulsion may vary from about 20% to 80% by volume, preferably in the range from about 40% to 60% by volume.

As pointed out heretofore, the present type of concentrate may be readily emulsified with hard water as,

for example, with water containing up to 600 p.p.m. of hardness. Other concentrates now on the market are relatively difficult to emulsify to form an oil-in-water emulsion wherein the hardness exceeds about 300 p.p.m. Thus, the concentrate of the present invention may be used with water having hardness in the range from about 300 to 600 p.p.m. of hardness.

What is claimed is:

1. A light colored, emulsifiable concentrate comprising in combination a major proportion of a white oil having a specific gravity of about 0.86 to 0.89, a Saybolt color of at least 10, a viscosity of about 355 to 375 SSU at 100, a pourpoint of <0 and a boiling range of within about 700°-990° F., about 0.01 to 0.5 volume percent of a sodium petroleum sulfonate concentrate wherein the sulfonate has a molecular weight of about 460-480 and comprises about 61-65% of said concentrate; 0.25 to 3.0 volume percent of a phenyl monoether of triethylene glycol, and about 0.5 to 3.0 volume percent of a tertiary amine prepared by condensing two amino hydrogen atoms of a primary alkyl amine in which the alkyl group is derived from soya oil with ethylene oxide having the formula

where n is 1 to 5 and preferably 3.

2. A light colored, tobacco desuckering emulsion comprising about 20-80% water and about 80-20% by volume of the composition of claim 1.

3. A light colored, emulsifiable concentrate comprising

ing in combination a major proportion of white oil, having a specific gravity of about 0.86 to 0.89, a Saybolt color of at least 10, a viscosity of about 355 to 375 SSU at 100, a pourpoint of <0 and a boiling range of within about 700°-990° F., about 0.10 vol. percent of a sodium petroleum sulfonate concentrate wherein the sulfonate has a molecular weight of about 460-480 and comprises about 61-65% of said concentrate; about 0.75 vol. percent of a phenyl monoether of triethylene glycol, and about 1.25 vol. percent of a tertiary amine prepared by condensing two amino hydrogen atoms of a primary alkyl amine in which the alkyl group is derived from soya oil with ethylene oxide having the formula

where n is 1 to 5 and preferably 3.

4. A colored, tobacco desuckering emulsion comprising about 20-80% water and about 80-20% by volume of the composition of claim 3.
